(57) **CLAIM**

The ornamental design for a hands-free door opener, as shown and described.

DESCRIPTION

FIG. 1 is a perspective view of the hands-free door opener showing the new design;

FIG. 2 is a front view of FIG. 1;

FIG. 3 is a rear view of FIG. 1;

FIG. 4 is a right profile view of FIG. 1;

FIG. 5 is a left profile view of FIG. 1;

FIG. 6 is a top view of FIG. 1;

FIG. 7 is a bottom view of FIG. 1;

FIG. 8 is a view showing an application for FIG. 1;

FIG. 9 is a perspective view of another hands-free door opener showing the new design;

FIG. 10 is a front view of FIG. 9;

FIG. 11 is a rear view of FIG. 9;

FIG. 12 is a right profile view FIG. 9;

FIG. 13 is a left profile view of FIG. 9;

FIG. 14 is a top view of FIG. 9;

FIG. 15 is a bottom view of FIG. 9; and,

FIG. 16 is a view showing an application for FIG. 9.

The broken lines in these drawings illustrate environmental features only and form no part of the claimed design. The shade lines shown represent surface shading and not surface ornamentation, color, or material type.

The claim is shown with a symbolic break in its length. The appearance of any portion of the article between the break lines forms no part of the claimed design.

1 Claim, 14 Drawing Sheets
